UNITED STATES PATENT OFFICE.

SAMUEL M. KIRSHNER, OF PHILADELPHIA, PENNSYLVANIA.

DESIGN FOR A WALL PAPER.

Application filed September 11, 1928. Serial No. 28,112. Term of patent 3½ years.

To all whom it may concern:

Be it known that I, SAMUEL M. KIRSHNER, a citizen of the United States, residing at Philadelphia, county of Philadelphia, State of Pennsylvania, have invented the new, original, and ornamental Design for a Wall Paper, of which the following is a specification, reference being had to the accompanying drawings, forming part thereof.

The figure is a plan view of a wall paper showing my new design.

I claim:

The ornamental design for a wall paper as shown.

SAMUEL M. KIRSHNER.
